UNITED STATES PATENT OFFICE.

EARL M. GLASS, OF PORT HURON, MICHIGAN.

GUARD-RAIL SOCKET.

1,120,048.

Specification of Letters Patent.

Patented Dec. 8, 1914.

Application filed September 16, 1913. Serial No. 790,099.

To all whom it may concern:

Be it known that I, EARL M. GLASS, citizen of the United States, residing at Port Huron, in the county of St. Clair and State of Michigan, have invented certain new and useful Improvements in Guard-Rail Sockets, of which the following is a specification.

This invention relates to new and useful improvements in fastening devices such as 10 are employed in mounting the terminals of stair rails and the like to the wall or other supporting structure.

It is customary in mounting railings of all types, such as deck-rails on boats or 15 ships, stair-way rails, and the like, to employ supporting cups or flanges which are attached to the wall, deck, post, or other supporting structure, and are provided with screw-threaded bosses or sleeves which receive the 20 threaded terminals of the rails. There has been a long felt want for a device of this character which may be cheaply manufactured, will be durable and efficient in its action, and constructed in such manner that 25 it may be quickly and readily applied to attach the rails to the supporting structure with a minimum expenditure of time and labor. Realizing the existence of the above conditions, I aim, therefore, to provide in 30 my invention a device of the character set forth which will consist of a minimum number of parts so constructed and designed that, when assembled, they will constitute a 35 guard rail socket meeting all of the above-named requirements.

The above and additional objects are accomplished by such means as are illustrated in the accompanying drawings, described in the following specification and then more 40 particularly pointed out in the claims which are appended hereto and form a part of this application.

With reference to the drawings, wherein I have illustrated the preferred embodiment 45 of my invention as it is reduced to practice, and throughout the several views of which similar reference numerals designate corresponding parts, Figure 1 is a longitudinal section taken through the guard rail socket 50 and the supporting structure to which it is attached; Fig. 2 is a top plan view of the preferred form of the device, the neck being shown in section to more clearly illustrate the interior arrangement of parts; Fig. 3 is

a detail perspective view of the base plate in 55 disassembled position; and Fig. 4 is a top plan view of a modified form of the device, the neck being shown in section in this figure.

Before proceeding to the description of 60 the drawings, it is desirable to emphasize the fact that while the device of this invention has been designed with particular reference to the mounting of guard rails for ship decks and the like, has been illustrated, 65 and will be hereinafter described in that connection, it may nevertheless be employed with equal efficiency in attaching rails, posts, fenders, or any other structure embodying terminally threaded pipes or rods which are 70 to be attached to walls, posts, floors, or some other similar supporting structure.

Proceeding now to the description of the drawings, the preferred embodiment of this invention, as best illustrated in Fig. 1, includes a base plate 10, a flanged pipe receiving cup 11, and an anchoring bolt 12. The base plate 10 is, as illustrated, preferably rectangular in shape, being formed of a metallic plate which may be casted or 80 pressed from iron, steel, copper, brass, or any other desired material which may be found most desirable.

The base plate 10 may be reinforced to lend the desired rigidity and strength by 85 forming an annular centrally disposed outstanding ring 13, four corner enlargements 14, and radially extending ribs 15 connecting the ring and enlargements. It is obvious, however, that the plate may be simply of a flat nature without in any way departing from the spirit of this invention. The ring 13 of the preferred embodiment defines a central opening which is formed in the plate and is adapted to receive the 90 shank of the anchoring bolt 12, as will be hereinafter more fully disclosed. The corner enlargements 14 are provided with threaded bores which are indicated at 16 and are designed to receive bolts, screws or 100 other suitable fastening devices which are employed in securing the rail receiving cup 11. This rail receiving cup 11 consists of a cup-shaped body portion or shell 17, extending from the base edge of which is a 105 laterally directed flange 18. On the outer edge of the flange 18 is formed an annular flange or rim 19 which extends at right

angles to the plane of the flange 18 and is adapted to incase the base plate 10 when the base plate and cup are in assembled relation. The flange 18 is formed at its four corners with bolt receiving holes or orifices, which are indicated at 20, and are countersunk to provide for the reception of the bolt or screw heads, as will be readily observed upon reference to Fig. 1. It is now to be noted that the cup body or shell portion 17 is of less diameter than the base plate 10, and is reduced at its upper terminal, being internally screw-threaded thereat to receive the screw-threaded terminal of the rail, illustrated conventionally at 21.

As a means for securing the base plate 10 to the wall, as illustrated in Fig. 1, there has been provided an anchoring bolt, which is preferably of the expansion type. This bolt includes a shank 22 having a head 23 of any desired design. The shank 22 is screw-threaded in the usual manner, and is tapered at its lower terminal, as illustrated at 24. A pair of expanding plates 25 and 26 are placed on the bolt shank and are adapted to be expanded to bite into the wall in the well known manner when the bolt is threaded inwardly. Upon reference to Fig. 1, it will be noted that, if so desired, a washer may be interposed between the head of the bolt and the base plate.

The actual construction and arrangement of the preferred form of this invention being thus disclosed, it now remains to describe briefly the various modifications to which the structure heretofore described may be subjected.

As illustrated in Fig. 4, the base plate may be made in the nature of a circular body and the flanges of the rod receiving cup formed correspondingly. In this connection, it is to be noted that the shape of the various elements is usually an arbitrary matter which will be governed entirely by the requirements presented in the various applications of the retaining device. It is, therefore, desirable to emphasize the fact that the present invention is directed to the broad idea of providing a base plate, an anchoring bolt, and a rod receiving cup, rather than in the particular shape or design of the device.

The manner in which the various parts are assembled will be readily observed upon reference to Fig. 1. The bolt shank is passed through the central opening of the base plate, and is then threaded into the members 25 and 26, which have previously been disposed in the receiving opening formed in the deck. After the bolt has been threaded inwardly to bring the base plate 10 in the desired engagement with the deck, the member 11 is attached by the threading of the screws 20 into the receiving bores 16 in the base plate. It now re-

mains to thread the terminal of the guard rail 21 into the threaded terminal of the body portion or shell 17.

In reduction to practice, I have found the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

In regard to the employment of the expanding plate hereinbefore described, it may be well to mention that when the rail fastening device of this invention is applied to metallic ship decks or the like, a machine bolt is used in securing the base plate. It has been found in practice that the expanding plates should be used on the lag screws only when the device is applied to cement or brick structures.

What I claim is:—

1. In a device of the character described, a base plate having a central opening, screw-threaded bores formed at its corners, an expansible anchoring bolt having its shank passed through the opening and its head bearing against the upper face of the base plate for securing the base plate to a supporting structure, a shell member removably mounted on the base plate and including an annular body member having its outer end restricted and internally screw-threaded, a laterally extending outwardly directed flange formed on the inner end of the annular body member, and a peripheral flange formed on the said first-mentioned flange and extending at right angles thereto, being disposed when in assembled position to incase the base plate, and bolts insertible through the said lateral flange and threaded into the said bores for securing the shell member to the base plate.

2. In a device of the character described, a base plate, means for securing the base plate to a supporting structure, and a shell member adapted to be detachably secured to the base plate and to form a cover therefor, said shell member including an annular body member having an internally screw-threaded restricted outer end, a laterally extending outwardly directed flange formed on the inner end of the shell member, and a peripheral flange formed on the said lateral flange and extending at right angles thereto, being adapted to engage against the edge of the said base plate when in assembled position.

3. In a device of the character described,

a base plate, and a shell member having an internally screw-threaded outwardly extending neck, said shell member being removably mounted on the base plate and 5 completely inclosing the same.

4. In a device of the character described, a base plate, an expandible anchoring bolt passed through the plate for securing the plate to a supporting structure, and a shell 10 member removably mounted on the base plate said shell member including an annular body member having an internally threaded restricted neck, and a peripheral flange adapted to embrace the edge of the 15 base plate, whereby the shell member completely incloses the plate.
5. In a device of the character described, a base plate, and a shell member removably

mounted thereon, said shell member including an annular body member having an outwardly extending flange formed at its lower terminal, and a peripheral flange formed on the outwardly extending flange, said outwardly extending flange being adapted to engage respectively with the upper face and 20 edge of the base plate, and an internally threaded restricted neck formed on the outer terminal of the shell member, said neck being adapted to receive the threaded terminal of a rail or similar member. 25

In testimony whereof I affix my signature in presence of two witnesses.

EARL M. GLASS. [L.S.]
